TABLET CONTAINER AND DISPENSER

Enock Ancker, Fort Bayard, N. Mex.

Application May 15, 1943, Serial No. 487,171

2 Claims. (Cl. 206—42)

1

My invention relates to the disposition and handling of tablets formed of medicated material and contoured in the nature of small disks, squares and the like, and has among its objects and advantages the provision of a sanitary container for the tablets wherein novel means are incorporated to the end that one tablet at a time may be easily removed from the container.

In the accompanying drawing:

Figure 1 is a perspective view of the container. Figure 2 is an enlarged sectional view along

Figure 3 is a perspective view of a tablet retain-

Figure 4 is a perspective view of a relatively

Figure 5 is a face view of a second tablet, thick body perforated to house the tablets.

Figure 6 is an edge view of the sheet of Fig-

Figure 7 is a sectional view taken along the line

In the embodiment of the invention selected

for illustration, Figures 1 and 2 illustrate a container or package 10 of such size as to be conveniently carried in a pocket on the person. This container comprises a relatively thick cardboard body 12 having perforations or cells 14 for loosely receiving tablets 16. To one face of the body 12 is adhesively secured a retaining sheet 18, as of thin paper, which sheet is deformed to provide depressions 20 for partly housing the tablets. These depressions project outwardly from the body 12 and are respectively aligned with the perforations 14.

To the other face of the body 12 is adhesively secured a second sheet 22, which may comprise paper, and which is provided with perforations 24 closely spaced in circular arrangement to provide easily detached disks breakout portion 25 overlying the perforations 14 to constitute barriers for the tablets 16. The disks 25 are of larger diameter than the perforations 14 to provide sanitary covers for the perforations 14, and the disks 25 are unglued with respect to the body 12 so as to tear easily from the sheet 22. Thus the tablets 16 lie loosely in the perforations 14, but are restrained by the sheet 22 so as to be held in the body 12.

A cover 27 is provided for the skeleton structure comprising the body 12 and the two sheets 18 and 22. This cover is folded back upon itself and attached to the skeleton structure by a staple 26, with the staple located slightly inwardly

2

of one end of the cover so that this end may serve as a tab 28 underneath which the other end of the cover may be inserted. This cover is of such size as to fold about the skeleton structure to enclose the latter inside the cover.

To remove a tablet, the cover 27 is opened, as by pulling its free end from underneath the tab 28, and the bulge defining one of the recesses 20 is pressed inwardly of the respective perforation 14, which causes the tablet to tear one of the disks from the sheet 22 and drop from the perforation 14.

The container or package may be made up in different sizes. This is also true of the perforations 14, which may be made in different sizes and shapes in accordance with the specific type of tablet to be loaded in the container.

Without further elaboration, the foregoing will so fully explain my invention, that others may, by applying current knowledge readily adapt the same for use under various conditions of service.

I claim:

1. A tablet container and dispenser comprising a body formed with spaced, circular tablet receiving openings therethrough, tablets in the openings and said tablets being of greater thickness than the body, a cover sheet on the body having outwardly depressed sections therethrough to accommodate the protruding portions of the tablets, a second cover sheet on the body enclosing the tablets in the openings and the said second cover sheet having circular closures for the openings, and a circular series of frangible connections between the second cover sheet and each of the closures, the radius of said circular series of frangible connections being of greater length than and concentric with the circular openings whereby the tablets may be dispensed by pressure upon the protruding portion to break the frangible connections.

45 2. A tablet dispenser and container comprising a body formed with spaced, circular tablet receiving openings therethrough, tablets in the openings and said tablets being of greater thickness than the body, a cover sheet on the body having outwardly depressed sections therethrough to accommodate the protruding portions of the tablets, a second cover sheet on the body enclosing the tablets in the openings and said second cover sheet having circular closures for the openings of greater diameter than the diameter of the openings and a circular series of frangible connections between each closure and the second

cover sheet forming spaces therebetween so that the connections and spaces will overlie the body of the dispenser maintaining sanitary conditions within the openings and whereby the tablets may be extruded through the second cover by pressure upon the outwardly protruding portion of the tablet.

ENOCK ANCKER.
